[57] CLAIM

The ornamental design for a cookware pan, as shown and described.

DESCRIPTION

FIG. 1 is a front elevational view of a cookware pan showing my new design, the rear elevational view being a mirror image;

FIG. 2 is a side elevation view of my design;

FIG. 3 is an opposite side elevational view of FIG. 2;

FIG. 4 is a top plan view of my design;

FIG. 5 is a bottom plan view of my design; and,

FIG. 6 is a cross-sectional view of my design.
